UNITED STATES PATENT OFFICE.

HENRY BOWHALL, OF CEDAR SPRINGS, MICHIGAN.

WRENCH.

SPECIFICATION forming part of Letters Patent No. 374,928, dated December 20, 1887.

Application filed August 15, 1887. Serial No. 246,983. (No model.)

To all whom it may concern:

Be it known that I, HENRY BOWHALL, a citizen of the United States, residing at Cedar Springs, in the county of Kent and State of Michigan, have invented new and useful Improvements in Wrenches, of which the following is a specification.

My invention relates to improvements in wrenches; and it consists in a certain novel construction and arrangement of parts, fully set forth hereinafter, and specifically pointed out in the claim.

In the accompanying drawings, Figure 1 is a side view of the wrench with the handles shown closed. Fig. 2 is a longitudinal central section of the same. Fig. 3 is a similar view with the handles separated and the spring-pawl disengaged from the ratchet. Fig. 4 is a rear view of the wrench.

Referring by letter to the drawings, A designates the main shank of the wrench, to the upper end of which is rigidly secured the upper jaw, B, having a serrated under side, and the lower end of the main shank is provided 25 with the forwardly-extending sleeves or loops C C.

D designates the sliding or ratchet shank, sliding in the loops C C and having the lower jaw, E, secured to the upper end, provided 30 with a serrated upper side to bite against the serrated under side of the upper jaw. The lower jaw is extended rearwardly to form the loop F, which embraces and slides on the main shank to guide the motion of the upper end 35 of the sliding shank. The lower end of the shank D is fashioned into a handle, D', and the inner side of the said shank is provided with a series of ratchet-teeth, as seen at G.

H designates a swinging handle, pivoted at 40 the upper end to the lower end of the main shank, thus enabling it to be swung away from the handle D' or drawn close up to the same. In a small recess or opening, i, in the upper end of the handle H is pivoted the pawl I, adapted 45 to engage the ratchet G, and K is a small lever or handle secured to the said pawl on the outer side of the handle H, adapted, when pressed toward the handle H, to raise the pawl out of engagement with the ratchet.

A small spring, L, is placed on the stud l, depending from the under side of the end of the lever K, and the inner end of the said

spring bears in a socket, h, in the outer side of the handle H. The tendency of this spring is to press the lever K outwardly, and thus 55 normally hold the pawl I in engagement with the ratchet.

It will be readily seen that when the handle H is drawn toward the handle D' the jaws of the wrench cannot be moved, as the spring-pawl is firmly engaged in the ratchet; also, when the handle H is swung outwardly, the jaws cannot be separated, as the spring-pawl is still engaged in the ratchet; but in this position the jaws can be drawn together, as the 60 pawl will slip over the ratchet-teeth, and by pressing upon the end of the small lever K the pawl may be disengaged and the jaws separated.

One important advantage gained by providing the wrench with the spring-pawl is that 70 it may be used (although provided with flat jaws) as a pipe-wrench. To apply it as a pipe-wrench the spring-pawl is raised and the jaws are pressed firmly against opposite sides of the pipe. The pawl is now released 75 and allowed to engage in one of the ratchet-teeth, and the handle H is drawn toward the handle D', thus acting as a lever to force the lower jaw very tightly against the pipe until the serrations on the inner sides of the jaws 80 are pressed into the material of the pipe on each side. This grip may be taken in a moment, and when it is desired to release the pipe for a new hold it is simply necessary to separate the handles and press the handle of 85 the pawl.

After a grip has been taken with this wrench, although it is very quickly taken and very readily released, the wrench may be dropped, and it will still maintain its grip upon the 90 pipe. With some wrenches now in use the grip depends upon the motion of the wrench to turn the pipe, and when the said motion has ceased the wrench loses its hold; but in this wrench the grip remains firm until the handles are separated and the spring-pawl released.

The lever K extends sufficiently forward to be within reach of the operator's thumb. Thus the wrench can be worked with one hand; 100 also, the free end of the lever K is formed with an operating knob or enlargement to more readily receive the pressure of the thumb; also, the handles D' and H fit close together,

so one hand can span and grasp them. The outer sides of the said handles are rounded, as shown, to more readily fit the hand.

Having thus described my invention, I 5 claim—

In a wrench, the combination of the shank D, having the lower jaw, E, and loop F made integral with it at its upper end, and provided with the ratchet-teeth G on its inner side, with 10 the main shank A, having the upper jaw, B, made integral with it at its upper end and provided with the loops C C at its lower end, the lever-handle H, pivoted to the lower end of the shank A and provided with the pawl-re- 15 cess i, the pawl I, pivoted in said recess and

engaging the ratchet-teeth G, the thumb-lever K, secured to the said pawl, extending downward therefrom, and provided with the inwardly-standing pin or stud l, and the spring L, seated in the recess h in the lever H, and 20 surrounding said stud and forcing the pawl into engagement with the ratchet-teeth G, substantially as specified.

In testimony that I claim the foregoing as my own I have hereto affixed my signature in 25 presence of two witnesses.

HENRY BOWHALL.
